United States Patent Office

Des. 203,621
Patented Feb. 1, 1966

203,621

TABLE TOP GAS CANDLE OR SIMILAR ARTICLE

Harold I. Gross, 1721 Coldwater Canyon,
Beverly Hills, Calif.

Filed Feb. 5, 1965, Ser. No. 83,704

Term of patent 14 years

(Cl. D48—2)

FIGURE 1 is a side elevational view of a table top gas candle or similar article, partly in section, showing my new design;

I claim:

The ornamental design for a table top gas candle or similar article, as shown.
